US00D656242S

(12) **United States Design Patent**
MacDonald et al.

(10) **Patent No.:** US D656,242 S
(45) **Date of Patent:** ** Mar. 20, 2012

(54) **LANDSCAPING BLOCK**

(75) Inventors: **Robert A. MacDonald**, Plymouth, MN (US); **Stephen Tyson Homeyer**, Argyle, TX (US)

(73) Assignee: **Keystone Retaining Wall Systems, Inc.**, Bloomington, MN (US)

(**) Term: **14 Years**

(21) Appl. No.: **29/386,465**

(22) Filed: **Mar. 1, 2011**

(51) LOC (9) Cl. **25-01**

(52) U.S. Cl. **D25/113**

(58) **Field of Classification Search** D25/102–118, D25/136, 138, 140, 151, 152, 153, 156–162, D25/164; D21/484–491, 499–504; 405/16, 405/284, 286; 52/503–505, 574, 575, 596–612; 404/27–42

See application file for complete search history.

(57) **CLAIM**

The ornamental design for a landscaping block, as shown and described.

DESCRIPTION

FIG. 1 is a front perspective view of an embodiment of a landscaping block according to my new design.

FIG. 2 is a front plan view of the landscaping block of FIG. 1.

FIG. 3 is a back plan view of the landscaping block of FIG. 1.

FIG. 4 is a top plan view of the landscaping block of FIG. 1.

FIG. 5 is a bottom plan view of the landscaping block of FIG. 1.

FIG. 6 is a left side plan view of the landscaping block of FIG. 1.

FIG. 7 is a right side plan view of the landscaping block of FIG. 1.

FIG. 8 is a front perspective view of an embodiment of a landscaping block according to my new design.

FIG. 9 is a front plan view of the landscaping block of FIG. 8.

FIG. 10 is a back plan view of the landscaping block of FIG. 8.

FIG. 11 is a top plan view of the landscaping block of FIG. 8.

FIG. 12 is a bottom plan view of the landscaping block of FIG. 8.

FIG. 13 is a left side plan view of the landscaping block of FIG. 8.

FIG. 14 is a right side plan view of the landscaping block of FIG. 8.

FIG. 15 is a front perspective view of an embodiment of a landscaping block according to my new design.

FIG. 16 is a front plan view of the landscaping block of FIG. 15.

FIG. 17 is a back plan view of the landscaping block of FIG. 15.

FIG. 18 is a top plan view of the landscaping block of FIG. 15.

FIG. 19 is a bottom plan view of the landscaping block of FIG. 15.

FIG. 20 is a left side plan view of the landscaping block of FIG. 15.

FIG. 21 is a right side plan view of the landscaping block of FIG. 15.

FIG. 22 is a front perspective view of an embodiment of a landscaping block according to my new design.

FIG. 23 is a front plan view of the landscaping block of FIG. 22.

FIG. 24 is a back plan view of the landscaping block of FIG. 22.

FIG. 25 is a top plan view of the landscaping block of FIG. 22.

FIG. 26 is a bottom plan view of the landscaping block of FIG. 22.

FIG. 27 is a left side plan view of the landscaping block of FIG. 22.

FIG. 28 is a right side plan view of the landscaping block of FIG. 22.

FIG. 29 is a front perspective view of an embodiment of a landscaping block according to my new design.

FIG. 30 is a front plan view of the landscaping block of FIG. 29.

FIG. 31 is a back plan view of the landscaping block of FIG. 29.

FIG. 32 is a top plan view of the landscaping block of FIG. 29.

FIG. 33 is a bottom plan view of the landscaping block of FIG. 29.

FIG. 34 is a left side plan view of the landscaping block of FIG. 29.

FIG. 35 is a right side plan view of the landscaping block of FIG. 29.

FIG. 36 is a front perspective view of an embodiment of a landscaping block according to my new design.

FIG. 37 is a front plan view of the landscaping block of FIG. 36.

FIG. 38 is a back plan view of the landscaping block of FIG. 36.

FIG. 39 is a top plan view of the landscaping block of FIG. 36.

FIG. 40 is a bottom plan view of the landscaping block of FIG. 36.

FIG. 41 is a left side plan view of the landscaping block of FIG. 36; and,

FIG. 42 is a right side plan view of the landscaping block of FIG. 36.
